DIGGING TEETH FOR LOADING MACHINE
DIGGING BLADES

Raymond Q. Armington, Shaker Heights, and
William F. Klun, Euclid, Ohio, assignors to
The Euclid Road Machinery Co., Euclid, Ohio,
a corporation of Ohio

Application October 11, 1947, Serial No. 779,344

5 Claims. (Cl. 37—110)

1

This invention relates to improvements in oscillating digging teeth immediately in advance of a digging blade.

An object of the present invention is to provide digging teeth in front of and closely adjacent to a blade adapted to move forward in a digging path, the purpose of the teeth being to slit or break up the ground immediately in front of the digging blade.

Another object of the present invention is to provide a novel support for digging teeth positioned substantially upon a digging blade which is inclined rearwardly and upwardly.

Another object of the invention is to provide novel mechanism for oscillating digging teeth of the type described above.

Still another object of the invention is to provide digging teeth of the type described in combination with a belt conveyor adapted to carry away the material loosened by the teeth and specifically the combination wherein the mechanism for oscillating the teeth is driven through the head pulley of the conveyor.

Other objects and advantages of our invention will be apparent from the accompanying drawings and description and the essential features will be set forth in the appended claims.

In the drawings,

Fig. 1 is a side elevational view of a conveyor loader equipped with our improved digging teeth;

Fig. 2 is a fragmental top plan view of the machine of Fig. 1 omitting all of the parts not necessary to the understanding of the present invention;

Figs. 3 and 4 are enlarged fragmental sectional views taken along the lines 3—3 and 4—4 respectively of Fig. 2, while

Fig. 5 is a completely sectioned view of a portion of the Fig. 3 view.

While our invention is adapted for use with many types of digging blades, we have chosen to illustrate the same in connection with a conveyor loader of the type more fully described and claimed in the copending application of Raymond Q. Armington, Serial No. 777,887, filed October 4, 1947. Such a device is equipped with an earth digging blade in generally horizontal position adapted to dig the earth and feed the same on to a belt conveyor. It is difficult with such apparatus to dig hard materials or gummy earth without first using a scarifier or some other device for breaking up the earth before processing the same with a conveyor loader. With our im-

2

proved device the entire job can be accomplished in one operation.

We will briefly describe the conveyor loader of our copending application sufficiently so that the present invention may be understood. This conveyor loader is drawn by a tractor a portion of which is shown at 10 as having parallel endless tracks 11 and a yoke 12 pivoted to the tractor at 13 and connected by a hitch 14 to the drawbar 15 of the conveyor loader. The hitch 14 is fully described and claimed in the copending application of Stanley Mayner and Frank L. Kapel, Serial No. 513,702, filed December 10, 1943, issued as Patent No. 2,488,676 on November 22, 1949. The drawbar is connected with a torque tube 16 which in turn is rigidly connected with two L-shape frame members 17 and 18 which are pivotally connected at 19 to side frame members 20 which form part of a main frame supported on two crawler tracks 21. A motor 22 on this frame supplies power for driving all of the necessary apparatus. An hydraulic jack 23 mounted on the frame is connected with the rearward extension 15a of the drawbar so that operation of the jack raises and lowers the member 17 and the forward portions of the side frame members 20. A tubular frame member 24 extends between the side frame members and at its mid point, on a ball and socket joint 25, supports the main frame 26 of a belt conveyor. The upper end of the conveyor frame is supported on a cross member 27 and generally vertical struts 28. This is all clearly shown in the above mentioned copending application Serial No. 777,887.

Referring now to Figs. 1 and 2, the conveyor frame 26, in operative position, extends at an angle to the center line of the side frame members 20 and therefore at an angle to the drawbar 15 and the general path of travel of the device as it is pulled behind the tractor. The conveyor belt 29 carries excavated earth upwardly and sidewardly and deposits the same over a head pulley 30 into a wagon travelling alongside the conveyor loader. Mounted at the forward end of the conveyor and just in front of the tail pulley 31 is a digging blade 32, formed in sections if desired and as shown in Fig. 2, having a bottom cutting edge 32a which is generally horizontal. This blade is secured to a supporting plate 33 by means not shown. The upper edge of the plate 33 overlies the belt 29 as clearly shown in Fig. 3 so that excavated earth is pushed up the

plate 33 by the travelling motion of the apparatus and falls on to the belt 29.

Digging teeth 34 and 35 constituting the present invention are supported for oscillating motion about generally vertical pivots 36 and 37 respectively. Since the construction connected with each tooth is substantially the same, one only will be described. The tooth 34 is V-shape in section providing a sharp digging point 34a in and a central ridge 34b running up the front of the tooth. The tooth is hollow in the rear and provided with a pocket 34c into which enters the front end of a lever 38. Lever 38 passes through an aperture or gap 32c between adjacent sections of blade 32. This lever is connected to the tooth by a pin 39 which passes through both of them. A short distance back from the forward end, the pivot pin 38 is welded into the lever at points 43 and 41. The upper end of this pin is of reduced diameter and carries a bushing 42 which is held in a bracket 43 which in turn is connected with a frame member 44 rigidly connected with the conveyor frame 26. Blade supporting plate 33 is also secured to frame angle member 44. A nut 45 threaded on the upper end of the pivot pin 38 holds these parts together. An opening 33a is provided in the plate 33 for access to the nut 45 and this opening is provided with an upwardly convex cover 46 secured to the plate 33 by means not shown. It will be noted from Fig. 3 that the rear edge 34d of the digging tooth is generally parallel to the blade 32. The oscillating means is connected with the rear end of lever 38 where a pivot pin 47 connects with a link 48 which in turn is mounted by bearing 49 on a crankshaft 50. In a similar manner, a lever 51 for operating tooth 35 is connected by link 52 and bearing 53 with a throw 50a on the crankshaft.

Referring to Figs. 2 and 4 the crankshaft 50 carries at its upper end a bevel gear 54 which meshes with bevel gear 55, both of which are suitably mounted for rotation in a housing 56. This housing is supported by brackets 57 on the conveyor frame 26. The bevel gear 55 is connected by shaft 58, universal joint 59, shaft 60, universal joint 61, shaft 62 and universal joint 63 with a set of bevel gears 64 and 65 driven by the head pulley 30. The opposite end of the head pulley is connected by bevel gears (not shown) with shaft 66 which in turn is driven by a suitable connection with motor 22. In the mid portion of the crankshaft 50 is a web or link 55b which connects the throws together. The lower end of the crankshaft is supported by bearing 67 in a bracket 68 which is connected to a beam 69 which in turn is rigidly mounted on the conveyor frame 26.

It results from the above construction that when motor 22 is operating, shaft 66 will drive the head pulley 30 which in turn will drive the bevel gears 65 and 64 so as to turn the shafts 62, 60 and 58 resulting in rotation of the bevel gears 54 and 55 and the rotation of the crankshaft 50. This will cause oscillating motion of the links 48 and 52 which will oscillate levers 38 and 51 respectively causing the teeth 34 and 35 to wobble from side to side as indicated in the dot-dash lines of Fig. 2. It will be noted that the oscillation of the point of the tooth is less than the width of the tooth measured crosswise of the digging blade, so that the resistance to the passage of the tooth through the earth is minimized. These teeth will break up or slit the earth immediately ahead of the blade 32 and if the teeth are spaced approximately as shown in Fig. 2, they will divide the strip of earth passing to the conveyor

belt into strips of approximately equal width if the portion of blade 32 to the left of the line A in Fig. 2 is used for cleaning up loose material rather than for virgin digging.

5 What we claim is:

1. In combination, a digging blade adapted to be moved forwardly, said blade sloping upwardly and rearwardly from its cutting edge, a conveyor sloping upwardly and rearwardly from said blade, said blade having a generally horizontal cutting edge, there being a gap in said blade, a tooth overlying said gap and closely adjacent said blade, said tooth having a forwardly-directed earth-slitting point, a generally vertical pivot, a lever extending below said conveyor and passing through said gap and mounted on said pivot for oscillation relative to said framework, means connecting the forward end of said lever with said tooth, means for oscillating said lever connected to the rear end thereof, and a common framework upon which said blade and said conveyor and said last mentioned means and said pivot with said lever are mounted.

2. In combination, a digging blade adapted to be moved forwardly, said blade sloping upwardly and rearwardly from its cutting edge, a conveyor sloping upwardly and rearwardly from said blade, said blade having a generally horizontal cutting edge, there being a gap in said blade, a tooth overlying said gap and closely adjacent said blade, a generally vertical pivot, said tooth having a forwardly directed earth-slitting point, a lever extending below said conveyor and passing through said gap and mounted on said pivot for oscillation relative to said framework, means connecting the forward end of said lever with said tooth, the rearward end of said lever extending beneath said conveyor, a crankshaft at one side of said conveyor, a link connection between said shaft and the rear end of said lever, means for rotating said crankshaft, and a common framework upon which said conveyor and said blade and said crankshaft and said last mentioned means and said pivot with said lever are mounted.

45 3. The combination of claim 2 wherein said last named means comprises a head pulley for said conveyor, means on said common framework for rotating said head pulley, and a driving connection between said head pulley and said crankshaft.

4. In a conveyor loader comprising a frame, a belt conveyor on said frame having a tail pulley and sloping upwardly and rearwardly from said pulley, means on said frame for moving said conveyor forwardly, and an earth cutting blade on said frame extending generally horizontally in front of said tail pulley and adapted to deliver earth to said conveyor as said conveyor and blade move forwardly, the combination therewith of a plurality of teeth in front of and closely adjacent said blade, each tooth of said plurality of teeth being spaced from another of said plurality of teeth to slit a strip of earth cut by said blade into a plurality of ribbons, all of said teeth extending generally parallel to the line of conveyor movement forwardly, each tooth tapering in width forwardly to provide an earth-slitting point, and means on said frame for wobbling said teeth from side to side, said means comprising a rearwardly extending lever on each tooth which lever extends longitudinally through an aperture in said blade.

5. In combination, a digging blade adapted to be moved forwardly, said blade sloping upwardly and rearwardly from its cutting edge, a conveyor

sloping upwardly and rearwardly from said blade, said blade having a generally horizontal cutting edge, there being a gap in said blade, a tooth overlying said gap and closely adjacent said blade, a generally vertical pivot, said tooth having a forwardly directed earth-slitting point, a lever extending below said conveyor and passing through said gap and mounted on said pivot for oscillation relative to said framework, means connecting the forward end of said lever with said tooth, means for oscillating said lever connected to the rear end thereof, and a common framework upon which said conveyor and said blade

and said last mentioned means and said pivot with said lever are mounted.
